SHELF TRIMMING

Moses Caplan, Boston, Mass.

Application November 24, 1934, Serial No. 754,632

6 Claims. (Cl. 41—10)

This invention relates to shelf trimming and the like, and aims to provide an improved, novel and simple form of trimming which will normally have a tendency to remain properly positioned upon the shelf edge and top, and substantially resist a tendency to slide back upon the shelf top under certain conditions of use.

In the drawings of one embodiment of my invention selected for illustration and description:

Fig. 1 is a perspective view of my novel trimming, with the elements in position to be applied to a shelf;

Fig. 2, a view on a larger scale, of the trimming in position on a shelf, both shown in section; and

Figs. 3 to 11, views similar to Figs. 1, 2, of modified forms of construction.

Referring to Figs. 1 and 2, my novel trimming comprises a shelf top section 1, the latter substantially the width of the shelf, and of any length, as it may readily be handled by the yard, and a shelf edge section 2 thereon, of paper or other suitable material, preferably having a sufficient body to assist in holding its shape, the edge section 2 adapted, Fig. 2, to depend vertically from the top section when in use, and to hang close to the front shelf edge 3. The edge section 2 is of suitable depth or height, as desired, and has a reinforcing ply of proper material 4 secured thereon, as by cement.

To make the shelf top section 1, Fig. 2, a sheet of material of proper dimensions is folded on itself longitudinally at a suitable point 5, which later becomes the edge of the top section 1, thus providing the top section 1 and edge section 2.

In making the fold, the edge section is carried back beneath the top section, and the fold laid in parallel relation to the shelf top section 1, Fig. 2, for a short distance, and either tightly compressed or cemented, or otherwise locked, and then offset, forming the overhang fold or lip 6. With the fold described, the additional ply 4 of material, plain or ornamental, is positioned to face outwardly, with its upper longitudinal edge substantially registering with the fold 6, and, with the section or ply 2, is bent sharply downward therefrom a short distance from the edge 5.

If, now, with the trimming applied as in Fig. 2, to the shelf A, in the course of ordinary use, putting dishes or other articles on the shelf and taking them from it, the shelf top section as a whole or in part is inclined to slide backwardly from the front edge, the edge section 2, rein-

forced by the ply 4 and by the fold 5, forming a pronounced offset of the top section and contacting with the shelf edge, as an anchoring element, will resist that tendency, and to some extent the tendency to slide longitudinally, and remain in position and act to hold the top section also in proper position.

At the present time, shelf trimming for the top and edge shelf sections is commonly made of one or more integral sheets, and bent downward at the proper point. Trimming made in this manner, however, will not so readily stay in position, as the normal curved edge or bend in the paper over the shelf edge will not hold it as desired. Nor, if the shelf edge section is a separate piece of material and simply cemented or secured to the shelf top section in an angular relation, will it restrain the top section from moving backward under slight pressure to do so.

If preferred, the fold or lip 6 may be formed by the use of perforations 7 through the paper lip, Fig. 3, or by stitching through it, as at 8, Fig. 4.

When made as shown in Figs. 1, 2, 3 or 4, the tendency of the shelf top section to slide rearwardly has a tendency to unfold the edge section 2 back on a line with the edge of the top section at the line 5 of the fold 6, or to open up the fold, which cannot be opened, and the smooth lip affords no resistance to sliding dishes or packages, which, if drawn forward, might have a tendency to catch the edge of the binding, if there were one, on the lip, and draw the shelf top trimming forwardly off the shelf.

In Figs. 5 to 11, I have shown modified forms of construction.

In Fig. 5, there is illustrated in perspective a construction comprising a second vertical ply 9, with a reinforcing ply 10 on its outer face, which two-ply member is secured by locking the upper edge 11 of the member to the inner face of the upper edge of the ply 2, and then locking or securing the two sheets as in Fig. 1.

An ornamental ply 10 may be so secured to the ply 9, if desired, as a convenient way of decorating it.

In Figs. 7, 8 and 9, I have shown in perspective and section a third modification, wherein the edge section 2 is reinforced on its inner face by a second ply 12, plain or decorated, stitched, as at 13, or otherwise secured to the member 2, leaving the second ply member 12 free above its stitching to be bent and adjusted at will, as at Fig. 8, or Fig. 9, to be cemented to the bottom face 14 of the shelf A, according to the thick-

ness of the shelf, the better to anchor the trimming against strong pushing or sliding action.

In this case, the ply 12 may be backed with a ply 15, which, in turn, may carry at its edge for convenience a strip of adhesive tape 16, or carry adhesive 17 on its edge.

In Figs. 10, 11, are shown a usual shelf edge sheet 2, with a longer anchoring sheet 18, with adhesive at 17, to be secured to the lower face 10 of a thicker shelf.

My invention is not limited to the particular embodiments shown herein.

I claim:

1. A shelf trimming comprising a sheet of material folded longitudinally on itself, thus forming a shelf top section and a shelf edge section, the material forming the edge section reinforced by a second ply, the first ply bent sharply away from the shelf top section at a point removed 20 from the folded edge thereof, to form an outstanding coverless lip, to outline the shelf edge and present an acutely angular, trimming anchoring formation to resist a tendency on the part of the trimming to slip from its position on the shelf.

2. A shelf trimming comprising a sheet of material folded longitudinally on itself, thus forming a shelf top section and a shelf edge section, the material forming the edge section reinforced 30 by a second ply, the first ply bent sharply away from the shelf top section at a point removed from the folded edge thereof with the upper edge of the reinforcing member adjacent the fold, to form an outstanding locked lip, to outline the 35 shelf edge and present an acutely, angular, trimming anchoring formation, to resist a tendency on the part of the trimming to slip from its position on the shelf.

3. A shelf trimming comprising a sheet of material folded longitudinally on itself thus forming a shelf top section and a shelf edge section, the material forming the edge section reinforced by a second ply, the first ply bent sharply away from the shelf top section at a point removed 40 from the folded edge thereof with the upper edge of the reinforcing ply adjacent the fold, the fold being locked to form an outstanding lip to outline the shelf edge and present an

angular trimming anchoring formation of plies of material parallel to the shelf edge to resist a tendency on the part of the trimming to slip from its position on the shelf.

4. A shelf trimming comprising a sheet of material folded longitudinally on itself, thus forming a shelf top section and a shelf edge section, the material forming the edge section reinforced by a second ply, the first ply bent sharply away from the shelf top section at a point removed 10 from the folded edge thereof and along the upper edge of the reinforcing ply; the fold being locked to form an outstanding lip to outline the shelf edge and present an angular trimming anchoring formation of plies of material parallel to the 15 shelf edge to resist slipping of the trimming; and a second reinforcing ply on the inside face of the shelf edge section attached to said edge section throughout a part of the area of the second reinforcing member only leaving a freely movable anchoring area thereof to engage the shelf bottom.

5. A shelf trimming comprising a sheet of material folded longitudinally on itself, thus forming a shelf top section and a shelf edge section, 25 the material forming the edge section reinforced by a second ply, the first ply bent sharply away from the shelf top section at a point removed from the folded edge thereof and stitched to the top section, to form an outstanding coverless lip, 30 to outline the shelf edge and present an acutely angular, trimming anchoring formation to resist a tendency on the part of the trimming to slip from its position on the shelf.

6. A shelf trimming comprising a sheet of material folded longitudinally on itself, thus forming a shelf top section and a shelf edge section, the material forming the edge section reinforced by a second ply, the first ply bent sharply away from the shelf top section at a point removed 40 from the folded edge thereof and cemented to the top section, to form an outstanding coverless lip, to outline the shelf edge and present an acutely angular, trimming anchoring formation to resist a tendency on the part of the trimming to 45 slip from its position on the shelf.

MOSES CAPLAN.
